(57) **CLAIM**

The ornamental design for a humidity control chamber, as shown and described.

DESCRIPTION

FIG. 1 is a front view of a humidity control chamber showing my new design;

FIG. 2 is a side view thereof;

FIG. 3 is a rear view thereof;

FIG. 4 is a side elevational view thereof;

FIG. 5 is a top view thereof;

FIG. 6 is a side and rear elevational view thereof; and,

FIG. 7 is a front elevational view thereof.

My new design is for a humidity controlled ornamental chamber used for storing expensive musical instruments such as electric guitars.
